UNITED STATES PATENT OFFICE.

GEORG KIRKEGAARD, OF NEW YORK, N. Y.

MACHINE FOR CAPPING BOTTLES.

No. 846,218.

Specification of Letters Patent.

Patented March 5, 1907.

Application filed December 21, 1905. Serial No. 292,693.

To all whom it may concern:

Be it known that I, GEORG KIRKEGAARD, a citizen of the United States, residing at the city of New York, in the borough of Brooklyn and State of New York, have invented certain new and useful Improvements in Machines for Capping Bottles, of which the following is a full, clear, and exact description.

10 My invention relates to a machine for applying caps or seals to bottles, and pertains particularly to the application of bottle-stoppers of the character described in my Patent No. 796,734.

15 The principal object of the invention is to provide a machine in which the entire operation of pressing the cap upon the bottle and turning the clamping-ring into locking engagement is properly and automatically performed, regardless of the irregularities in the heights of the bottles or shapes of their necks or any irregularities in the manufacture of the cap.

20 A further object of the invention is to provide a machine of simple, strong, and efficient character which is adapted to the needs of ordinary bottling works and which may be rapidly operated without any difficulty or skilled manipulation.

25 With these and other objects in view my invention consists in the construction, combination, location, and arrangement of parts, as hereinafter set forth and shown, and finally particularly pointed out in the appended claims.

30 Reference is also made to my companion divisional applications, Serial No. 293,277, filed December 26, 1905, and Serial No. 294,064, filed January 2, 1906.

35 In the drawings, Figure 1 is a side view, partly in section, of a complete machine embodying the principles of my invention. Fig. 2 is a front view of the same. Fig. 3 is a detail sectional-view of what I shall term the "main" operating-spindle. Fig. 4 is a detail sectional view showing the cap-applying head. Fig. 5 is a section on the line V V of Fig. 4 looking downward. Fig. 6 is a section on the line VI VI also looking downward.

40 Fig. 7 is a sectional view taken generally on the line VII VII of Fig. 4. Fig. 8 is a detail vertical sectional view of the cap-applying head. Fig. 9 is a sectional view on the line

IX IX of Fig. 3. Fig. 10 shows a detail bottom view of the bottle rest or support. Fig. 55 11 is a detail view of a modification. Fig. 12 is a bottom view of a cap which is applicable for use with the present invention.

The form of cap which is particularly adapted to use with this invention embodies 60 a circular plate with a lining of cork or packing-disk on its bottom face and having circumferential depending fingers which are forced into engagement with the usual bead or protuberance upon a bottle by a clamping- 65 ring. A form of clamping-ring which I have found satisfactory in practical use is illustrated particularly in Figs. 7, 8, and 12 of the drawings.

The cap is denoted by the reference character *a* and has three resilient depending fingers *b* equally spaced around its circumference. The interior of the cap has a lining *c*, of cork or analogous packing substance, so as to make a tight engagement with the top of a 75 bottle when pressed thereon. The clamping-ring *d* has a milled circumferential edge *e* and interior cam edges *f*, which correspond in number to the depending fingers *b* and are arranged to bear thereagainst, as shown particularly in Fig. 12. This ring is held in proper relation on the fingers by means of lips *g* on the cap coöperating with the lower edges of the fingers *b*, which are slightly flared outward for this purpose. It is evident that 80 the various fingers *b* will be cammed inward when the locking part *d* is turned with relation to the cap *a*. While the present invention is especially adapted for this form of cap, it is not strictly limited to such use, being applicable to a wide variety of caps besides the forms mentioned.

In carrying out my invention I make use of a vertically-moving cap-applying head, beneath which the already-filled bottle is 95 placed and which descends so as to completely apply the cap. In practice the operator places caps within the head with one hand at the same time he positions the bottle on its rest or support with the other. The machine works continuously at a rate suitable to the hand-manipulations required, so that caps are applied to the filled bottles very rapidly.

Referring now to the drawings, in which 105 like parts are designated by the same refer-

ence-signs, 10 denotes the main frame or casing of the machine, having power-shaft 11, with the usual pulley 12. The frame or casing 10 is made with an upright hollow standard 13, in which is guided a vertically-moving rod 14, projecting from the top thereof.

15 designates a pitman connection from the lower end of the rod 14 to a crank 16 on the main power-shaft.

10 17 denote brackets upon the standard 13, in which is guided the main operating-spindle 18. The main operating-spindle is conveniently connected to the vertically-reciprocating rod 14 by a cross-bar 19. While I 15 have shown this particular arrangement for obtaining vertical reciprocating motion of the main operating-spindle 18, I do not desire to be limited or restricted thereto, since it is evident that the main operating-spindle may 20 be reciprocated in any convenient way.

The lower end of the main operating-spindle 18 carries the cap-applying head 20, the details of which will be later more particularly described. The bottle or receptacle to be 25 sealed is placed beneath the cap-applying head and in axial alinement therewith, as shown at 21, being conveniently supported on a pad or mat 22 and being grasped by guiding-fingers 23 for this purpose.

30 24 indicates a bracket for supporting the pad 22, so as to permit a vertical adjustment thereof to accord the machine to bottles of every size.

The main frame or standard 13 has an extension 13^a, in which a threaded stud 24^a of the bracket 24 is received and adjusted by a nut 26.

35 A practical form of guiding or positioning fingers 23 for holding the neck of the bottle is 40 illustrated in Fig. 5 and comprises a V-shaped part 27, secured to a fixture 29 on the bracket 24 and having pads 28 in a position where they will contact with the bottle-neck. 23 indicates spring-fingers curved so as to permit

45 the ready insertion of the bottle, but having sufficient resiliency to close upon and hold the same in engagement with the pads 28 when the cap is applied. By means of the guiding-fingers 23 and the base-pad 22 the 50 bottles may be readily positioned into a predetermined relation in axial alinement with the main operating-spindle 18 and its cap-applying head. The fixture 29 is adjustable on the bracket 24 by means of bolts 25' in the 55 bracket and passed through a slot 25 in the fixture 29.

Referring now more particularly to Fig. 3, it will be seen that the main operating-spindle 18 is hollow throughout the major portion of its length and contains an independently-movable core 30, which directly carries the cap-applying head, as shown in Fig. 1. The core or shaft 30 is revoluble within the main operating-spindle 18 by virtue of

the antifrictional roller engagement 31, which 65 also permits a vertical axial movement of the core within the spindle. The upper end of the core or shaft 30 has a thrust connection 32 with a sliding block 33, spring-pressed downward by tension-spring 34 within the 70 main operating-spindle. 35 designates an adjustable attachment for this spring varied by manipulating the screw 36 and lock-nut 37. By this mechanism the core or shaft 30 is capable of revolving and of moving axially 75 within the main operating-spindle, its axial movement being resisted by a spring, the tension of which can be adjusted. I provide means for controlling the rotary and axial movements of the core or shaft 30 within the 80 main operating-spindle comprising cam-grooves 38 and the initial part 39 of which is in the plane of the spindle, while the terminal part 40 is inclined into a spiral or inclined direction.

85 41 indicates a stud upon the core or shaft 30 which engages the cam-groove 38, so that the core or spindle is moved by the cam-groove when it is forced inward against the tension-spring 34.

90 The cap-applying head 20, previously referred to, is attached to the lower end of the core or shaft 30. The cap-applying head comprises an exterior housing 42, which rotates with the core or shaft 30, but which has 95 a non-positive rotative engagement therewith, so as to permit slippage under certain circumstances. For this purpose the housing is held between a collar 43 on the core or shaft and an adjustment clamp-nut 44, an 100 intermediate spring crown 45 being interposed to give a considerable amount of friction. By this engagement the housing 42 is caused to ordinarily rotate with the shaft or core 30, but in case of unusual resistance the 105 spring crown 45 becomes ineffective to transmit further rotation, so that thereafter the parts slip with relation to one another.

110 The nut 44 may be adjusted upon the crown 45, so as to produce just enough friction to secure the locking engagement of the cap upon the bottle, as will be later described. When the adjustment is satisfactory the locking-bolt 44' is tightened so as to preserve the 115 adjustment secured.

120 The lower end of the core or shaft 30 has a swivel bearing-plate 46 thereon, the lower part of which is cupped, as shown at 47. 48 designates the central supporting stud or screw, and 49 indicates an ordinary ball-bearing raceway co-operating therewith, by which the bearing-plate is supported in freely-rotatable relation.

125 The housing 42 is made with a wide opening 50 on its lower face and has a number of swinging pawls 51, disposed around its circumference on vertical axes 52. 53 (see Fig. 7) designate ordinary leaf-springs, which

may be riveted to the respective pawls, so as to bear against the wall of the housing and press the pawls inward. In practice the inner edges of the pawls are made with a curved or flaring edge 54, the edge being also notched at 55 for a purpose which will later appear. The inward-swinging movement of the pawls 51 is limited by contact of their edges with the swivel bearing member 46.

10 In Fig. 11 I have illustrated a slight modification in which friction-pawls or cam-wedges 56 are substituted for the pawls 51. These would be used in place of the usual pawls 51 in case the outer edge of the clamping-ring were smooth.

15 The operation is as follows: The operator, being provided with a supply of caps and a quantity of filled bottles to be sealed, inserts a cap into the cap-applying head 20 by 20 merely pushing it upward therein until it abuts against the swivel bearing-plate 46. In this action the edges of the cap will ride against the flaring or beveled edge 54 of the pawls 51 until the edges eventually fall into 25 the notches 55. The spring-pressure of the pawls is effective to maintain the caps in this relation within the cap-applying head, the milled edges of the clamping-ring of the cap being engaged by the pawls, as clearly illus-

30 trated in Fig. 7. The operator now places a filled bottle upon the pad 22, its neck being guided by the guiding-fingers 23, it being in this way axially alined with the cap located in the cap-applying head, as above described.

35 The main operating-shaft 18, by virtue of the continuous movement of the driving-pulley 12 or any clutch mechanism, now descends until the cap rests upon the top of the bottle, as indicated in Fig. 4. The main operating- 40 spindle 18 continues to descend, however, and in its further movement the core or shaft 30 is pushed inward with respect thereto against the tension of the spring 34. During the initial part of this movement the core 45 merely recedes within the main operating-spindle without any circumferential movement, the stud 41 being guided by the rectilinear groove 38. During this time a continuous and increasing pressure is applied to

50 the cap to force the same against the bottle-neck on account of the increasing compression of the spring 34. After a certain movement the pressure becomes sufficiently great to compress the usual cork or packing ma-

55 terial within the cap into proper and sealing engagement with the bottle-neck, the stud 41 having by this time arrived at the top of the rectilinear grooves 39. Further descent of the main operating-spindle therefore causes

60 the studs 41 to ride upon the inclined grooves 40, so that the stud and core or shaft 30 are positively rotated through a portion of a revolution. On account of the swivel support of the bearing-plate 46 this rotary move-

ment is not transmitted to the cap which remains stationary in compressed relation upon the bottle; but the rotation is transmitted through the spring crown or friction-disk 45 to the housing 42, which rotates, with its connected pawls 51, in engagement with the milled edge of the clamping-ring of the bottle-cap. In this way the clamping-ring is turned, its cam edges forcing the usual clamping-fingers of the cap into locking engagement with the bottle. If now the main operating-shaft 18 has a return or upward movement, the housing 42 will rotate in the reverse direction; but in this case the pawls 51 will slip idly over the milled edges of the clamping-ring on the cap, so that the latter will not be disengaged. The main operating-shaft finally moves upward sufficiently to release the properly capped and sealed receptacle, which is thereupon placed by the attendant in the boxes for shipping and delivery.

What I claim is—

1. In a machine for supplying bottles with caps provided with an independently-movable locking-ring, means for holding the cap against turning movement on the bottle, and means for turning the ring, for locking the cap in place.

2. In a machine for supplying bottles with caps provided with a locking-ring, means for pressing the cap down upon, and holding it in close contact with, the neck of the bottle, and means for actuating said ring, independently of the cap, for locking the latter in place.

3. In a machine for capping bottles, a cap-applying head having means for receiving a cap with a clamping-ring, and means whereby the cap is pressed on the bottle and the clamping-ring subsequently turned.

4. In a machine for capping bottles, a cap-applying head having means for receiving a cap having a clamping-ring, means whereby the same is initially compressed upon the bottle, and means whereby the clamping-ring is subsequently rotarily engaged so as to be locked thereon.

5. In a machine for capping bottles, a cap-applying head adapted to receive and hold a cap having a locking part thereon, and means whereby said locking part is moved relatively to the cap to clamp the latter in place upon a bottle-neck.

6. In a machine for capping bottles, a cap-applying head adapted to grasp and hold a cap having a locking part by its engagement with such locking part, and means whereby said head is rotated to clamp said cap upon a bottle.

7. In a machine for capping bottles, a cap-applying head adapted to receive and hold a cap and having an independently-revoluble housing, and means whereby the cap is first

- depressed upon a bottle, and subsequently locked thereon by non-positive rotary movement of the housing.
8. In a machine for capping bottles, a cap-
5 applying head adapted to receive and hold a cap having a clamping-ring, and means whereby it is initially depressed and the clamping-ring subsequently rotated to clamp and lock the cap upon a bottle.
10. In a machine for capping bottles, a cap-
15 applying head adapted to receive a cap having a locking part, means in said head for grasping said part and turning it with relation to the cap and simultaneously pressing said cap upon a bottle.
10. In a machine for capping bottles, a cap-
20 applying head adapted to receive a cap having a locking part, means for pressing said cap upon a bottle, and means for turning
25 said locking part relatively to the cap.
11. In a machine for capping bottles, a cap-
30 applying head having means for engaging two separate parts of a cap, and imparting a relative movement thereto so as to lock the cap upon a bottle.
12. In a machine for capping bottles, a cap-
35 applying head having means for engaging two relatively movable parts of the cap, and imparting a relative movement thereto so as to lock the same upon a bottle.
13. In a machine for capping bottles, a cap-
40 applying head having means for engaging the cap and the usual clamping-ring thereof, and imparting a relative movement thereto.
14. In a machine for capping bottles, a cap-
45 applying head having means for engaging the cap and forcing it upon a bottle, and means for engaging the clamping-ring and applying a final rotary movement thereto.
15. In a machine for capping bottles, a vertically-movable main operating-spindle having a cap-applying head at its lower end, means for receiving a bottle in alignment with said spindle, and means whereby a cap
50 having a clamping-ring is initially pressed and the ring subsequently locked upon the bottle.
16. In a machine for capping bottles, a vertically-reciprocating main operating-spindle, a shaft guided therein and normally spring-pressed downward, a cap-applying head secured to said shaft, and means whereby the reciprocations of said main operating-spindle initially press the cap-applying head upon a bottle and subsequently rotate it.
17. In a machine for capping bottles, a reciprocating main operating-spindle, and a shaft having a cap-applying head guided to move initially rectilinearly and subsequently
60 rotarily within said main operating-spindle.
18. In a machine for capping bottles, a reciprocating main operating-spindle having an axially-movable core spring-pressed out-
ward therefrom and carrying a cap-applying head, and means whereby the core is first 65 pressed inward and subsequently turned when the cap is applied to a bottle.
19. In a machine for capping bottles, a reciprocating main operating-spindle having a shaft spring-pressed outward therefrom and adapted to have a rectilinear and subsequent circumferential movement, and carrying a cap-applying head, whereby the head is initially pressed and subsequently turned in applying a cap upon a bottle.
20. In a machine for capping bottles, a reciprocating main operating-spindle having a shaft spring-pressed outward therefrom and carrying a cap-applying head, and cam means for imparting an initial pressing and subsequent rotary movement to said cap-applying head.
21. In a machine for capping bottles, a hollow reciprocating spindle having a cam-groove in its wall, and a shaft spring-pressed 85 outward from said spindle and carrying a cap-applying head, and engaged by said cam-groove whereby it has an initial pressing and subsequent rotary movement.
22. In a machine for capping bottles, a reciprocating hollow spindle having a cam-groove in its wall, a shaft having a cap-applying head spring-pressed outward from said spindle and guided by said cam-groove, and an antifriction-bearing at the end of said 90 shaft to permit revoluble movement.
23. In a machine for capping bottles, a reciprocating spindle having a cam-groove and a cap-applying head guided by said spindle and groove to have an initial pressing and 95 subsequent rotary movement.
24. In a machine for capping bottles, a reciprocating spindle having a shaft spring-pressed outward therefrom, and a cap-applying head on said shaft and having a frictionally-engaged independently-revoluble housing.
25. In a machine for capping bottles, a reciprocating spindle having a cam-groove, a cap-applying head guided by said groove to have an initial pressing and subsequent rotary movement, and a pawl-carrying housing adapted to have a rotary movement frictionally 105 imparted to it.
26. In a machine for capping bottles, a reciprocating spindle having a spring-pressed shaft carrying a cap-applying head, said cap-applying head having a central swivel bearing-plate, and an outside housing adapted to be frictionally rotated thereby.
27. In a machine for capping bottles, a vertically-reciprocating spindle having a cap-applying head in spring-pressed engagement therewith, said cap-applying head having a housing frictionally engaged thereto, whereby 115 rotary movements of the cap-applying

head are non-positively imparted to said housing.

28. In a machine for capping bottles, a cap-applying head having a revoluble housing arranged to frictionally rotate therewith, and means for adjusting the degree of the frictional engagement.

In witness whereof I subscribe my signature in the presence of two witnesses.
